UNITED STATES PATENT OFFICE.

WILLIAM L. NEWMAYER, OF WILKINSBURG, PENNSYLVANIA, ASSIGNOR TO WESTINGHOUSE ELECTRIC & MANUFACTURING COMPANY, A CORPORATION OF PENNSYLVANIA.

AUTOMATIC STATION.

Application filed February 18, 1924. Serial No. 893,573.

To all whom it may concern:

Be it known that I, WILLIAM L. NEWMAYER, a citizen of the United States, and a resident of Wilkinsburg, in the county of Allegheny and State of Pennsylvania, have invented a new and useful Improvement in Automatic Stations, of which the following is a specification.

My invention relates to automatic stations and more particularly to protective devices to be utilized in the starting and the operation of the apparatus in automatic stations.

One object of my invention is to provide an automatic electrical translating station in which a rotating electrical device is provided with means for supplying lubricant to its bearings at a predetermined pressure before the device can be started.

Another object of my invention is to provide an automatic station comprising a rotating electrical machine, an exciter generator therefor and means for precluding the application of normal voltage to the machine until the starting current falls to a predetermined value and the exciter generator voltage rises to a predetermined value.

A further object of my invention is to provide a station, of the above-indicated character, in which the translating device is provided with an electrical heating element that is energized when the device is not running, for the purpose of maintaining the device at such temperature that its windings will not absorb moisture from the atmosphere.

A still further object of my invention is to provide a station, of the above-indicated character, that shall be simple and economical in construction and efficient and reliable in its operation.

In practicing my invention, I provide an electrical translating device, a source of energy for operating the same and a transformer for reducing the potential of the source of energy. The transformer has two sets of taps on its low potential windings, one for supplying energy to start the translating device and the other for supplying energy to operate the device under normal conditions. I also provide a starting circuit interrupter between the starting taps of the transformer and the translating device and a running interrupter between the

running taps and the translating device. 55 The various features of my invention are embodied in the electrical system which I further provide for controlling the actuation of these circuit interrupters.

I accomplish the first object of my invention by providing a contact-making pressure gauge for preventing closing of the starting circuit interrupter until lubricant is supplied to the bearings of the translating device at a predetermined pressure. 60 65

I accomplish the second object of my invention by providing means responsive to the current traversing the translating device during the starting period, co-operating with means responsive to the voltage of the exciter generator of the translating device to prevent opening of the starting interrupter and closing of the running interrupter until the starting current and the exciter generator voltage are within predetermined 70 75 limits.

For the purpose of maintaining the temperature of the translating device at a predetermined value when the device is not operating, I provide an electrical heating element disposed adjacent to the windings of the translating device, that is automatically connected through a transformer to the source of energy when the translating device is not operating and disconnected 80 85 therefrom when the device is operating.

In the accompanying drawings,

Figure 1 is a diagrammatic view of an electrical system in which my invention is embodied; and

Fig. 2 is a simplified schematic diagram of the same circuits in which similar reference numerals are applied to like pieces of apparatus.

Referring to Fig. 1 of the drawings, an 95 electrical translating device 1, is adapted to receive energy from a supply circuit 2 through the circuit interrupters 3, 4 and 5 and a transformer 6. The circuit interrupter 3, when closed, connects the supply 100 circuit 2 to the primary windings 7 of the transformer 6. The circuit interrupter 4, when closed, connects starting taps 8 of the transformer 6 to stator windings 9 of the translating device 1. The circuit interrupter 5, in like manner, connects running taps 10 of the transformer 6 to the windings 9. 105

In the drawing, the translating device 1 has been shown as a motor that is provided with an exciter generator 11, but that otherwise has no load connected thereto. For simplicity, it will be assumed that the translating device 1 is a synchronous motor operated as a condenser and connected to the circuit 2 for the purpose of maintaining the power factor or the voltage of the circuit 10 within predetermined limits. In view of this assumption, it might be desirable to have the translating device 1 start automatically in response to either voltage or power factor conditions in the circuit 2 15 and to operate under the control of such conditions.

I have not shown the apparatus for accomplishing such results but have merely shown a manually actuated switch 12 for 20 initiating and controlling the operation of the translating device 1. If it is desired to make the operation of the station automatically responsive to conditions in the circuit 2, the switch 12 may be replaced by 25 the contact members of a relay that is responsive to such conditions, but as the use of such a relay is well known in the art, it is not shown in the diagrams.

When it is desired to initiate the operation 30 of the translating device 1, the switch 12 is closed. It will be understood, of course, that the closing of this switch may be accomplished from a remote point by any other means well known in the art. 35 When the switch 12 is closed, a circuit is completed between an electric battery 13 and the operating coil 14 of a master relay 15, thereby causing this relay to effect disengagement of its contact members 16 and 40 engagement of its contact members 17. When the contact members 17 are engaged, a circuit is completed between the battery 13 and an operating coil 18 of the circuit interrupter 3 to cause the circuit interrupter 45 3 to be closed. The primary windings 7 of the transformer 6 are thereby connected to the supply circuit 2 and receive energy therefrom.

Engagement of the contact members 17 50 also completes a circuit extending from the battery 13 to a motor 19 through auxiliary contact members 20 of the circuit interrupter 5, which are engaged when the circuit interrupter 5 is open. The motor 19 55 is thus energized from the battery 13 and begins to operate a pump 21 that is connected to the motor 19 through a piston rod 22, a connecting rod 23, a crank 24 and a shaft 25.

The pump 21 is connected through a pipe 60 or conduit 26 to a reservoir 27 and through pipes or conduits 28, 29 and 30 to the bearings 31 and 32 of the translating device 1. When the pump 21 starts to operate, it 65 forces lubricant from the reservoir 27 into

the bearings 31 and 32 of the translating device 1 through the various connecting pipes or conduits, as shown.

A pressure gauge 33 that is connected to the pipe or conduit 29, is provided with a 70 pair of contact members 34 and a bridging member 35. When the pressure of the lubricant in the pipe or conduit 29 attains a predetermined value, the pressure gauge 33 expands to cause the bridging member 35 75 to engage the contact members 34. A circuit is thereby completed extending from the battery 13 through the contact members 17 of the master relay 15, a resistor 36, an operating coil 37 of the circuit interrupter 80 4, a pair of auxiliary contact members 38 of the circuit interrupter 3 that are engaged when the circuit interrupter 3 is closed, the contact members 34 of the pressure gauge 33 and the auxiliary contact members 20 85 of the circuit interrupter 5.

The coil 37 is thus energized to actuate the circuit interrupter 4 into its closed position, thereby connecting the starting taps 8 of the transformer 6 to the stator windings 9 of the translating device 1. The translating device 1 now receives energy at less than normal potential from the starting taps 8 of the transformer 6, and begins to rotate. 95

The exciter generator 11 has an armature member 39 that is mounted on the shaft of the translating device 1 and is directly driven thereby. The exciter generator 11 is also provided with a field-magnet winding 40 that is connected in parallel relation to the armature member 39. The terminals of the exciter generator are connected to the field-magnet windings of the translating device 1 through slip-rings 56 and 57 in such 100 manner that the field magnets of the device 1 are excited by energy supplied by the exciter generator 11. 105

As the speed of the translating device 1 increases, the speed of the armature member 39 of the exciter generator 11 and the voltage between its terminals likewise increase. When this voltage attains a predetermined value, the operating coil 44 of a relay 43 that is connected across the terminals of the exciter generator 11 is sufficiently energized to cause this relay to effect engagement of its contact members 45 and 46, respectively. 110

One of the conductors extending from the circuit interrupters 4 and 5 to the stator windings 9 of the translating device 1 is provided with a current transformer 47 that is directly connected to the operating coil 48 of a relay 49. When the current traversing the stator windings 9 exceeds a predetermined value, the proportionate current traversing the current transformer 47 and the coil 48 energizes the coil 48 to a sufficient degree to cause the relay 49 to effect dispersion. 115 120 125 130

gagement of its contact members 50. Thus, while a heavy starting current is traversing the stator windings 9 of the translating device 1, the contact members 50 are disengaged, but as soon as this current falls below a predetermined value, the contact members 50 are engaged.

When the contact members 50 are engaged, a circuit shunting the operating coil 37 of the circuit interrupter 4 is completed through the auxiliary contact members 38 of the circuit interrupter 3, the contact members 34 of the pressure gauge 33, the contact members 50 of the relay 49 and the contact members 45 of the relay 43, it being assumed that the voltage of the exciter generator 11 has risen to the predetermined value required to energize the coil 44 with sufficient strength to effect engagement of the contact members 45 before the contact members 50 of the relay 49 are engaged.

In the event that the contact members 50 become engaged before the contact members 45 are engaged, the circuit shunting the operating coil 37 of the circuit interrupter 4 will not be completed until the voltage of the exciter generator 11 rises to the predetermined value that is required for energizing the coil 44 sufficiently to cause the contact members 45 to be engaged. It does not matter in which sequence these events occur, as in either case the exciter generator voltage must rise to a predetermined value and the current traversing the stator windings 9 must fall to a predetermined value before the coil 37 can be short-circuited.

When the coil 37 is short-circuited, because of the events described above, it is de-energized to permit the circuit interrupter 4 to return to its open position. When the circuit interrupter 4 opens, a pair of auxiliary contact members 51 are engaged to complete a circuit extending from the battery 13 through the contact members 17, 51 and 46, respectively, to the operating coil 52 of the circuit interrupter 5. The circuit interrupter 5 is thereby closed to establish a circuit extending from the running taps 10 of the transformer 6 to the stator windings 9 of the translating device 1.

When the circuit interrupter 5 is closed, its auxiliary contact members 20 are disengaged to interrupt the circuit extending through the motor 19 which drives the lubricant pump 21. Operation of the motor 19 and the pump 21 is thereby stopped and lubricant is no longer supplied to the bearings 31 and 32 of the translating device 1 under pressure. It is only necessary that the lubricant be supplied to these bearings under pressure while the machine is being started, for as soon as lubricant has been forced into the bearings with sufficient pressure to float the shaft of the machine, the bearings may be automatically lubricated

by means of oil rings or any other well known means.

The running circuit interrupter 5 being closed, the translating device 1 is now operating under normal conditions as a synchronous motor. This operation continues so long as the switch 12 remains in its closed position. When the switch 12 is opened, however, the circuit extending through the operating coil 14 of the master relay 15 is interrupted to permit this relay to return to its de-energized condition. The contact members 17 of the relay 15 are then disengaged to interrupt the traversal of current between the battery 13 and all of the controlling means of the electrical system so that these means are de-energized to permit the station to return to its non-operating condition. This condition prevails so long as the switch 12 is open and whenever this switch is again closed, the cycle of operations above described is repeated.

When the master relay 15 is de-energized, its contact members 16 are engaged. The primary winding 58 of a transformer 59 is thereby connected to one of the phases of the supply circuit 2. The transformer 59 has a secondary winding 60 that is directly connected to an electrical heating element 61 that is disposed adjacent to the windings of the translating device 1. When the master relay 15 is de-energized, therefore, the heating element 61 is energized from the supply circuit 2 to maintain the temperature of the translating device 1 at such a value that its windings will not absorb moisture from the surrounding atmosphere.

As long as the station is not operating, the heating element 61 remains in its energized condition to maintain the temperature of the translating device 1 above a predetermined value. When the relay 15 is energized to cause initiation of the operation of the station, the contact members 16 are disengaged and the heating element 61 is no longer energized. As long as the translating device 1 is operating, there is no necessity for the heating element 61 to be energized, because the temperature of the translating device 1 is automatically maintained above the predetermined value at which its windings will absorb moisture from the atmosphere.

I have now completely described the structure and the operation of an electrical system in which the various features of my invention are embodied and this description may be summarized as follows:

First, the starting circuit interrupter cannot be closed until lubricant is supplied to the bearings of the translating device at a predetermined pressure.

Second, the running circuit interrupter cannot be closed until the current traversing the stator windings of the translating de-

vice has fallen to a predetermined value and until the exciter voltage has attained a predetermined value.

Third, the windings of the translating device are automatically maintained at a temperature above that at which they will absorb moisture from the atmosphere when the translating device is not operating.

It will be understood that the system embodying my invention is not limited to the specific details of construction and connections that have been shown in the drawings and described in the foregoing specification, as many changes and modifications may be made therein without departing from the spirit and scope of my invention, as set forth in the appended claims.

I claim as my invention:

1. In an automatic electrical translating station, the combination with a rotating electrical device provided with a plurality of bearings, means for supplying lubricant to the bearings under pressure, and means for automatically starting the rotating device under predetermined conditions, of means responsive to the pressure of the lubricant in the bearings for precluding starting of the rotating device until such pressure attains a predetermined value.
2. In an automatic electrical translating station, the combination with a rotating electrical device provided with a plurality of bearings, a supply of lubricant, means for forcing the lubricant into the bearings under predetermined conditions and means for automatically starting the rotating device in response to predetermined conditions, of means for rendering the lubricant-forcing means effective directly upon the occurrence of the conditions in response to which the device is to be started, and for maintaining such effectiveness until the device begins to operate under normal running conditions.
3. In an automatic electrical translating station, the combination with an electrical translating device and a source of energy, of an electrical heating element disposed adjacent to the windings of the translating de-

vice and adapted to be connected to the source of energy under predetermined conditions and means for automatically maintaining the connection of the heating element to the source of energy while the translating device is operating.

4. In an automatic electrical translating station, the combination with an electrical translating device and a source of energy, of an electrical heating element disposed adjacent to the windings of the translating device and adapted to be connected to the source of energy under predetermined conditions and means for automatically precluding connection of the heating element to the source of energy while the translating device is operating.

5. In an automatic electrical translating station, the combination with an electrical translating device, a source of energy, and automatic means comprising a master relay for initiating and controlling the operation of the translating device, of an electrical heating element disposed adjacent to the windings of the translating device for preventing said windings from absorbing moisture while the translating device is not operating and means associated with the master relay for maintaining the connection of the heating element to the source of energy while the translating device is not operating.

6. In an automatic electrical translating station, the combination with an electrical translating device, a source of energy, and automatic means comprising a master relay for initiating and controlling the operation of the translating device, of an electrical heating element disposed adjacent to the windings of the translating device for preventing said windings from absorbing moisture while the translating device is not operating, and means associated with the master relay for precluding connection of the heating element to the source of energy while the translating device is operating.

In testimony whereof, I have hereunto subscribed my name this 15th day of February, 1924.

WILLIAM L. NEWMAYER.
